UNITED STATES PATENT OFFICE.

WALTER D. CHURCH, OF CALEDONIA, ILLINOIS.

SILO-ROOF.

1,109,109.

Specification of Letters Patent.

Patented Sept. 1, 1914.

Application filed April 26, 1913. Serial No. 763,842.

To all whom it may concern:

Be it known that I, WALTER D. CHURCH, a citizen of the United States, residing at Caledonia, in the county of Boone and State of Illinois, have invented certain new and useful Improvements in Silo-Roofs, of which the following is a specification.

This invention relates to silos, and more particularly to a new and novel roof, or covering for the same.

An object of this invention is to provide a simple, durable, and inexpensive construction formed of a plurality of sections, which are hingedly connected to the upper edge of the silo in such a manner that they may be swung upward, thus opening the top of the silo and allowing the ensilage to be put in the silo from the top of the same. These sections will further form extensions for the sides of the silo, increasing the capacity of the same, and when the ensilage has settled the sections may be folded inward, forming a roof or covering for the silo.

Another object of this invention is to provide a novel and efficient ventilating means for the interior of the silo, which is mounted upon the top of the same, thereby allowing the fumes, etc., to pass outward and prevent the ensilage, which is next the roof of the silo, from deteriorating, as is commonly the case in silos now in use.

A still further object of this invention is to connect the hinged sections of the roof to the interior of the sides of the silo by adjustable means whereby the sections may be rigidly held in any desired position.

With the foregoing and other objects in view, this invention consists in such novel features of construction, combination and arrangement of parts as will be hereinafter more fully described, illustrated in the accompanying drawings and claimed.

In describing the invention in detail, reference will be had to the accompanying drawings wherein like characters of reference designate like or corresponding parts throughout the several views, and in which,

Figure 1 is the top plan view of a silo having the improved roof and ventilating means applied thereto. Fig. 2 is a fragmentary view of a portion of the improved roof showing, in dotted lines, the manner of connecting the sections to the top of the silo. Fig. 3 is a cross-sectional view through the top of the improved roof and silo, showing the sections closed, in solid lines, and opened,

in dotted lines. Fig. 4 is a detail sectional view of an inner end of one of the sections showing a part of the ventilator secured thereto. Fig. 5 is a detail sectional view of the inner end of another of the sections of the roof. Fig. 6 is a detail view of the means for connecting the sections to the inner sides of the silo, and for holding them in adjusted positions; and, Fig. 7 is a detail perspective view of a member employed in holding the various sections in place.

In referring to the drawings by numeral 1 designates the sides of the silo which is constructed in the usual manner, being circular in cross section, and which has hingedly connected to its upper edge a plurality of triangular-shaped sections 3, 4, and 5. Each of the triangular-shaped sections has its base which is disposed over the outer edge of the silo 1, curved as is clearly shown in the drawings. This feature is employed to increase the attractiveness of appearance of the device, as well as to cause the roof to conform to the shape of the silo. The triangular-shaped section 4 has a cut-out portion formed therein, which cut-out portion has door 6, forming a closure for the same. The door 6 hingedly connected to the section 4, as at 7, and forms a means for egress into the silo whenever desired.

The various sections of the roof of the silo are hingedly connected, as has been heretofore stated, to the upper end of the side 1 of the silo by means of hinges 8. The section of the hinges 8, which are secured to the sections of the roof, are peculiarly shaped, as is shown in Fig. 3 of the drawings, having bars disposed between a portion thereof, and the sections so that sections will be properly held in their respective positions thereby. Rigidly connected to the inner surface of each of the sections, at a point substantially midway of the ends thereof, are members 10 which have ears 11 depending therefrom. Bars 12 are pivotally connected to the ears 10, as at 13, and have formed on their inner and lower ends 14, projections 15. The projections 15 extend laterally in relation to the longitudinal lines of the members 12, and are bent about second members 16, which are pivotally connected to ears 17. The ears 17 are formed upon members 18 which are secured to the inner surface of the sides 1 of the silo at any desired point, as is clearly shown in Fig. 3 of the drawings. The upper ends of

the members 16 are provided with projections 19 which are bent about the members 12. The bending of the extensions 15 and 19 about the members 12 and 16 respectively connect these two members in slidably engagement with each other. For rigidly holding the members 12 and 16 in any desired adjusted position, thumb-screws 20 are provided. The thumb-screws 20 are mounted in the end of the member 16 which have the extensions 19 formed thereupon and engages the member 16, as is clearly shown. The section 3 of the roof has a substantially conically shaped member 21 secured to its inner end by means of bolts 22 and a plate 23. The substantial, conically shaped member 21 has its apex cut away, as is clearly shown in the drawings, and also has a plurality of openings 24 serially arranged within its side. The openings 24 receive the angular ends 25 of the plates 26. Each of the sections of the roof, with the exception of the section 3, have a plate 26 secured to the inner surface thereof, and near their inner ends by means of bolts of any other suitable securing means 27. These plates 26 are secured to the sections of the roof so that when the sections are closed or swung inwardly so as to form a roof for the silo, the annular ends 25 thereof will be seated in the openings 24, thereby aiding in holding the sections in place and preventing the inner ends of the sections from sagging.

A hood 28, which is constructed of sheet metal, or similar material, and which has its base 29 formed so as to fit snugly over the inner ends of the sections of the roof, is provided. This hood 28 has an angularly-shaped cap 30 mounted upon the sides 31 thereof. The sides 31 are provided with plurality cut-out portions, so as to form an efficient and practical ventilator for the interior of the silo. The air or fumes contained within the silo will, naturally, pass upward, and by the provision of the conically shaped member 21, which has its apex cut away, and the hood 28, will be allowed to pass out of the silo, thus preventing the deterioration of the ensilage near the roof of the silo.

When it is desired to fill the silo with the ensilage, the various sections of the roof are swung upwardly, as is indicated in dotted lines in Fig. 3 of the drawings. The thumb-screws 20 are then adjusted and the sections are held rigidly in place during the entire operation of the filling of the silo. When it is desired, the sections will also form extensions for the sides of the silo, thus increasing the capacity of the latter, and allowing of a greater amount of green ensilage to be put in the silo. After the ensilage has settled, the sections may then be swung inwardly, as is shown by solid lines in Fig. 3 of the drawings; and when the hood 28 is put up

on the inner ends of the sections, a water-proof and efficient roof is provided for the silo; and also the ventilating means for the interior of the same.

In practical fields, certain minor features of construction, combination and arrangement of parts may necessitate alterations to which the patentee is entitled, provided such alterations are comprehended within the scope of what is claimed.

What is claimed is:

1. A silo roof composed of a plurality of triangularly-shaped sections hingedly connected to the upper edge of the sides of a silo and ventilating means permanently connected to the inner end of one of said triangularly-shaped sections and releasably engaging the inner ends of the remaining sections to support the same.

2. A silo roof composed of a plurality of triangularly-shaped sections hingedly connected to the upper edge of the sides of a silo, means connected to each of said triangularly-shaped sections and to the interior of the sides of the silo for holding said sections in adjusted positions and ventilating means connected to the inner end of one of said triangularly-shaped sections and fitting beneath the remaining sections to releasably support the same.

3. In a silo roof, the combination of a plurality of triangularly-shaped sections hingedly connected to the upper edge of the sides of a silo, adjustable bracing means connecting each of said sections directly to the interior of the sides of the silo for holding said triangularly-shaped sections in adjusted positions, a conically-shaped member secured to one of said sections said conically-shaped member forming a ventilator for the interior of the silo, and a hood fitting over the inner ends of said sections and forming a means for preventing water from entering the silo through said conically-shaped member.

4. In a silo roof, the combination of a plurality of triangularly-shaped sections hingedly connected to the upper edge of the sides of a silo, adjustable bracing means connecting each of said sections directly to the interior of the sides of the silo for holding said triangularly-shaped sections in adjusted positions, a conically-shaped member secured to one of said sections said conically-shaped member forming a ventilator for the interior of the silo, a hood fitting over the inner ends of said sections and forming a means for preventing water from entering the silo through said conically-shaped member, said conically-shaped member provided with a plurality of openings through its side and means mounted upon the inner sides of said sections adapted to be inserted in said openings or aiding in holding said sections in place.

5. In a silo roof the combination of a plurality of sections hingedly connected to the upper edge of the sides of a silo, a collar provided with an open upper end rigidly secured to the inner face of one of said sections and provided with a plurality of openings, pins carried by the other of said sections for fitting into the openings of said collar whereby said collar will releasably engage said sections and support the inner ends of said sections, and means for holding said sections in an adjusted position.

6. In a silo roof the combination of a plurality of sections pivotally connected to the

sides of the silo, a ventilator rigidly secured 15 to one of said sections, means carried by the remaining sections to releasably engage said ventilator whereby said ventilator will support the inner-end portions of said sections, and adjustable supporting means for holding 20 said sections at a desired angle.

In testimony whereof I affix my signature in presence of two witnesses.

WALTER D. CHURCH.
